UNITED STATES PATENT OFFICE

WILLIAM O'CONNOR, OF SYRACUSE, NEW YORK.

PULLEY-GUARD.

1,277,466.

Specification of Letters Patent.

Patented Sept. 3, 1918.

Application filed February 21, 1918. Serial No. 218,484.

To all whom it may concern:

Be it known that I, WILLIAM O'CONNOR, a citizen of the United States, residing at Syracuse, in the county of Onondaga and State of New York, have invented certain new and useful Improvements in Pulley-Guards; and I do declare the following to be a full, clear, and exact description of the invention, such as will enable others skilled in the art to which it appertains to make and use the same.

My invention has for its object to provide an extremely simple and inexpensive, yet a highly efficient and durable guard for metal pulleys; the device being so constructed as to prevent the spokes of the pulley from coming in contact with belt hooks, broken belts, workmen's clothing, etc., thus preventing a great deal of trouble and injury which now often occurs by such incidents.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a side elevation of a split steel pulley showing the application of the invention, parts being broken away and in section;

Figs. 2 and 3 are transverse sections of Fig. 1 on the planes of the lines 2--2 and 3--3 thereof; and

Fig. 4 is a disassembled perspective view of one of the guard disks.

In the drawings above briefly described, the numeral 1 designates a shaft, 2 a pulley hub secured on said shaft or loose thereon as the case may be, 3 designates the metal rim of the pulley, and the numerals 4 and 5 designate the spokes which extend from the hub 2 to the rim 3. The rim 3 is formed of semi-circular sections abutting each other at 6 and the edges of each of said sections are turned inwardly at 7 primarily for reinforcing purposes and it is my intention that these inwardly turned edges shall assist in holding the guard disks yet to be described in place. The spokes 4 are located between the ends of the two rim sections and are provided with lateral feet 8 secured to said sections and spaced inwardly a slight distance from the inturned edges 7. The spokes 5 however are located at the ends of

the two rim sections and are bolted together at 9 to hold the two halves of the pulley assembled, the outer ends of the spokes 5 being increased in width as shown at 10 and abutting the inturned edges 7.

The construction so far described is a well known form of split steel pulley and it is the object of my invention to provide guard disks 11 which will be particularly adaptable to the opposite sides of this particular pulley although being well suited for use upon other makes. Each disk 11 is preferably formed of two substantially semi-circular sections 12 and 13 overlapping each other and provided in their inner edges with notches 14 which coöperate in forming an opening to receive the shaft 1. The portion of the disk sections 12 which overlap the sections 13, are preferably off-set from the body portions of said sections 12 as shown at 15 in order that the outer side of each disk will be free of obstructions when the two sections are secured together by screws 16 or by any other preferred means.

The central portions of the disks 11 abut the ends of the hub 2 and are thus held against inward movement while the edges of said disks are received within the rim 3 between the inturned edges 7 thereof and the feet 8, so that both inward and outward movement of such edges is prevented. Also, the edges of the disks are notched as seen at 17 to receive the enlarged ends 10 of the spokes 5.

The disks 11 may be constructed of thin metal, card board, or any other preferred material and when such material is other than metal, the joints between the two sections 12 and 13 of each disk will preferably be secured by cementing or gluing a strip of fabric or the like thereover. In cases where metal is used, screws such as 16 will preferably though not necessarily be employed. In fact, it may not be necessary in some cases to provide any securing means between the two sections 12 and 13, but some such means will by preference be employed.

The invention is extremely simple, inexpensive, and easily applied, and it will be highly efficient for preventing any objects from coming in contact with the spokes or other interior parts of the pulley. It will thus be seen that accidents will be avoided and that consequently the shop may be run at greater efficiency since it will not be necessary to shut down the machinery to disen-

tangle belts, repair damaged pulleys, and the like which have been injured for instance by a belt hook slipping into engagement with the spokes thereof, and care for workmen who have possibly been injured by entanglement of some article of clothing in the spokes of a pulley. It may further be explained that the accumulation of dust and dirt within the pulley rim is prevented and thus the danger of fire is decreased.

Since probably the best results are obtained from the several specific details shown and described, these details are by preference employed, but within the scope of the invention as claimed, numerous minor changes may well be made.

I claim:

1. In combination, a pulley comprising a metal rim having inwardly turned edges, a hub, and means connecting said hub and rim; together with a pair of guard disks for the sides of the pulley, said disks having central openings to receive the pulley shaft, 20 the edges of said disks being received within the rim of the pulley and abutting the in-turned edges thereof to prevent outward movement of said disks, while the centers of said disks abut the ends of said hub to 25 prevent inward movement of the former.
2. In combination, a pulley comprising a metal rim having inwardly turned edges, a hub, and spokes connecting said rim and hub and having feet secured to the inner 30 side of the latter in spaced relation with the

in-turned edges of said rim; together with a pair of guard disks for the sides of said pulley, said disks having central openings to receive the pulley shaft, the edges of said disks being received within the rim and located between said feet and said in-turned edges of said rim, whereby said disks are held against both inward and outward movement at their outer edges, the central portions of said disks abutting the ends of said hub to prevent inward movement of said portions. 40

3. In combination, a pulley including a metal rim formed of two semi-circular sections having their edges turned inwardly, 50 a hub, and spokes extending between said hub and rim, the spokes at the ends of said sections being increased in width at their outer ends and bolted together, while the other spokes are provided with feet secured to the rim; together with a pair of guard disks for the sides of the pulley, said disks abutting the ends of the hub and having openings to receive the pulley shaft, the edges of said disks being received within 55 said rim between said seat and said in-turned edges and having notches receiving said enlarged spoke ends. 60

In testimony whereof I have hereunto set my hand in the presence of two subscribing 65 witnesses.

WILLIAM O'CONNOR.
